UNITED STATES PATENT OFFICE.

RALPH SNOWDEN FETTER, OF TRENTON, NEW JERSEY.

APPARATUS FOR RESTORING WORN-OUT REAMERS.

No. 857,877.

Specification of Letters Patent.

Patented June 25, 1907.

Application filed January 23, 1907. Serial No. 353,736.

To all whom it may concern:

Be it known that I, RALPH SNOWDEN FETTER, a citizen of the United States, and residing at Trenton, in the county of Mercer and State of New Jersey, have invented certain new and useful Improvements in Apparatus for Restoring Worn-Out Reamers, of which the following is a specification, such as will enable those skilled in the art to which it appertains to make and use the same.

This invention relates to worn out reamers and particularly to means for restoring the same to their original dimensions and usefulness.

The invention involves the use of a hydraulic press and of a die of novel form and said invention is fully disclosed in the following specification, of which the accompanying drawing forms a part, in which the separate parts of my improvement are designated by suitable reference characters in each of the views, and in which:

Figure 1 is a side elevation of a hydraulic press which I employ; Fig. 2 a longitudinal section of my improved die for use in upsetting worn out reamers, said section being on the line 2—2 of Fig. 3, and showing a reamer in position in said die; Fig. 3 an end view looking in the direction of the arrow x of Fig. 2; and, Fig. 4 a side view of the reamer shown in Fig. 2 but on a reduced scale.

My invention is particularly adapted for use in upsetting and restoring tapered reamers *a*, and in practice a hydraulic press *b* having a vertically movable plunger *b*² and a horizontally movable plunger *b*³ and of any preferred form or construction is employed.

In the practice of my invention, I provide a die *c* shown in Figs. 1 and 2, which comprises a bottom member *c*² and a top member *c*³, the left hand end of the bottom member *c*² being provided with an upright portion or shoulder *c*⁴ against which the top member *c*³ abuts. In the adjacent faces of the die members *c*² and *c*³ and at the left hand end of said die is an oblong chamber *c*⁵, and at the right hand end of said die and formed in the adjacent faces of the separate die members *c*² and *c*³ is an oblong chamber *c*⁶, and the chambers *c*⁵ and *c*⁶ are connected by a central longitudinal passage or chamber *c*⁷ which is circular or cylindrical in cross section and of a diameter equal to or slightly greater than the greatest diameter of a reamer of the class referred to before it is worn or used. The chambers *c*⁵ and *c*⁶ may be of any desired

transverse dimensions but the comparative lengths thereof and the comparative length of the chamber or passage *c*⁷ are shown in the drawing. The reamer *a* is provided with the usual shank *a*² and the length of said reamer and its shank is greater than that of the length of the die as clearly shown in Fig. 2. I also provide an adjusting collar or sleeve *d* adapted to fit in the member *c*² and through which the smaller and fluted end of the reamer passes, together with a shank collar or sleeve *e* adapted to fit in the chamber *c*⁶ and to project therefrom and through which the shank *a*² of the reamer passes.

In practice, the worn part of the reamer between the points *f* and *f*² is first heated to the required degree, after which the collar or sleeve *d* is placed on the fluted end of the reamer, and the collar or sleeve *e* on the shank of the reamer, and said reamer is then placed in the bottom portion of the die, after which the top portion of the die is placed in position as shown in Figs. 2 and 3. The die *c* is then placed in position on the bed of the press *b* and beneath the vertical plunger *b*², and pressure is applied to the said vertical plunger so as to firmly hold the die in place. Pressure is then applied to the horizontal plunger *b*³ which is forced forwardly into contact with the end *a*³ of the shank *a*² of the reamer *a* and into contact with the end of the collar or sleeve *e* which projects from the die and that part of the reamer between the points *f* and *f*² is upset and shortened so that it fills the passage or chamber *c*⁷. The collar or sleeve *d* is intended to prevent the twisting or breaking of the fluted and reduced end of the reamer in the above described operation and hold it in proper shape or position, and after said operation the die is taken out of the press and the reamer taken out of the die and said reamer is redressed and retempered or refinished.

My invention is not limited to any kind or class of press, any press which will operate in the manner described being sufficient.

In the herein described operation the reamer is shortened to a certain extent usually about five-eighths of an inch or according to the amount to which it had previously been worn below its normal size.

It will be observed that the part *c*⁴ of the die serves to hold the reamer against longitudinal movement when pressure is applied to the opposite end thereof in the above de-

scribed operation, but any other suitable means may be provided for accomplishing this result.

Having fully described my invention, what I claim as new and desire to secure by Letters Patent, is:—

1. A die for use in upsetting worn reamers comprising two separate parts, said parts being provided in their adjacent faces and their opposite ends with cutaway portions forming longitudinal end chambers connected by a central longitudinal passage in which in practice, the reamer to be upset is placed, that part of said die in which said chambers and passage are formed being shorter than the reamer to be upset, a collar or sleeve adapted to be mounted on the fluted end of the reamer and to fit in one of the said chambers, and another collar or sleeve adapted to be mounted on the shank of the reamer and to fit in the other end chamber of the die and to project from said die.
2. A die for use in upsetting worn reamers comprising two separate parts, said parts being provided in their adjacent faces and

their opposite ends with cut-away portions forming longitudinal end chambers connected by a central longitudinal passage in which in practice, the reamer to be upset is placed, that part of said die in which said chambers and passage are formed being shorter than the reamer to be upset, a collar or sleeve adapted to be mounted on the fluted end of the reamer and to fit in one of the said chambers, and another collar or sleeve adapted to be mounted on the shank of the reamer and to fit in the other end chamber of the die and to project from said die, said die being provided with means to prevent the longitudinal movement of the reamer when pressure is applied to the shank end thereof.

In testimony that I claim the foregoing as my invention I have signed my name in presence of the subscribing witnesses this 21st day of January, 1907.

RALPH SNOWDEN FETTER
